UNITED STATES PATENT OFFICE.

LOUIS H. RAMSEY, OF LEXINGTON, KENTUCKY.

ILLUMINATED POSTER, BULLETIN, AND SIGN BOARD.

Application filed October 24, 1923. Serial No. 670,614.

To all whom it may concern:

Be it known that I, LOUIS H. RAMSEY, a citizen of the United States, residing at Lexington, in the county of Fayette and State of Kentucky, have invented certain new and useful Improvements in Illuminated Poster, Bulletin, and Sign Boards, of which the following is a specification.

My invention relates to improvements in illuminated poster, bulletin and sign boards and more particularly to advertising sign boards such as are distributed along streets and highways and upon the hillsides.

In the past it has been customary to provide illumination for advertising sign boards consisting of lamps arranged in front of the signs and supported by various shaped arms extending from the top thereof. The lamps of necessity have reflectors designed for the purpose of deflecting the rays of light from the passing public and for concentrating the rays of light upon the sign. However, disadvantages are connected with this method of illuminating advertising signs, in that the several lights are reflected directly and nearly perpendicular to the sign thereby concentrating intensive illumination in spots, while other portions lack sufficient illumination. The supporting arms of the lamps, for the purpose of partially overcoming the spotted and unsatisfactory non-uniform illumination of the sign, are generally lengthened to a point whereby considerable light is dissipated before reaching the sign, thereby requiring additional candle power to procure sufficient illumination. Furthermore, the wind, rain, ice, and other elements in time cause disarrangement of the lamp supports and they are, therefore, the source of continuous trouble and expense. Besides these disadvantages connected with the present method of illuminating advertising sign boards and the like the unsightly appearance of the supporting arms and reflectors detract from the sign during the daylight period.

The objects of my invention are to provide means whereby advertising sign boards may be efficiently, economically and attractively illuminated by lamps concealed from view of the readers of the sign; to provide means whereby the rays of light start in close proximity and are directly concentrated upon the sign thereby avoiding dissipation of the light rays and reducing the present candle power required to

clearly visualize the sign; to provide means whereby the light rays are reflected into holes or depressions on the sign; to provide means whereby the light rays are reflected from a reflector to another reflector thereby making use of a ray of light many times in the illumination of a sign.

My invention consists in providing lamps mounted within supporting columns of a sign board and adjacent the corners thereof in such a manner as to permit the rays of light to travel in a plane almost parallel to the front of the sign board; in providing a reflector at each end of the sign board designed to reflect the rays of light inwardly at an angle adapted to illuminate all normal depressions or elevations within the sign and adapted to cause the rays of light to be reflected from one reflector toward the other reflector, and vice versa.

My invention also consists in the details of construction, and in the combination and arrangement of parts as herein set forth and claimed.

In the drawings:

Fig. 1 is a front elevational view of a stationary sign board with the supporting columns broken away;

Fig. 2 is a horizontal section taken on a line corresponding to 2-2 in Fig. 1;

Fig. 3 is a vertical section taken on a line corresponding to 3-3 in Fig. 1;

Fig. 4 is a perspective view of my lamp and reflector support and adjusting mechanism showing the supporting rod broken away and a fragmental view of my zig-zag reflector shown in dotted lines; and

Fig. 5 is a fragmental view of my light deflecting device.

In the embodiment of my invention as illustrated and which shows a preferred construction a usual sign board 1 adapted to receive an advertising sign on its front is supported by hollow columns 2, containing lamps 3 and 3', respectively, having reflectors 4 and 4', respectively, secured to vertical tubes 5 and 5' by clamping brackets 6.

As shown in Fig. 1 lamp 3 is positioned adjacent the lower horizontal edge of sign board 1 and slightly in front of the face of the sign, and reflector 4 is adjusted to reflect the rays of light from lamp 3 across substantially the one-half of the front of the sign board comprising the portion below a line drawn from a corner 1' of the sign

board adjacent lamp 3 diagonally across the sign board to corner 1''. Lamp 3' is positioned adjacent the upper horizontal edge and slightly in front of the face of the sign, 5 and reflector 4' is adjusted to reflect the rays of light from lamp 3' across substantially the one-half of the front of the sign board comprising the portion above the line drawn from corner 1' to corner 1''. 10 Lamp 3 may be positioned adjacent the upper horizontal edge of the sign board and lamp 3' may be positioned adjacent the lower horizontal edge of the sign board, the primary object being that each lamp shall 15 illuminate substantially one-half of the front surface of the sign not illuminated by the other lamp.

The construction of the mechanism on each end of the sign being substantially the 20 same, only one side need be described in detail.

The upper and lower ends of vertical tubes 5 and 5' are axially pivoted in transverse supports 7 and 8, respectively, secured to 25 the inner surface of the walls of the columns. The lower ends of the vertical tubes project through cylindrical base 9 and are secured thereto by screws 10 threaded in vertical sockets 11, respectively, integral 30 with base 9, respectively, each having indicating finger 12 fixed to the side thereof and adapted to cooperate with graduating scale 13 fixed to the upper sides of transverse support 8. Thumb screw 14 threaded 35 in hole 15 in cylindrical base 9 is adapted to secure the cylindrical base and vertical tube 5 against rotary movement. The zig-zag reflector 16 made of any suitable material such as metal, nickel-plated to insure 40 a bright and reflecting surface, is fixed to the inner side of vertical tube 5 as by spot welding points of contact 16' to the vertical tube. The zig-zag reflector extends from transverse support 7 downwardly to transverse support 8 and is so adjusted that when 45 light rays from lamp 3 are properly adjusted upon the front surface of sign board 1 the outer edge 16'' of the zig-zag reflector is inclined sufficiently toward the center of 50 the sign board so that the rays of light from lamp 3 are reflected inwardly for the purpose of illuminating depressions and elevations such as may be on the surface of the sign. The reflector 16 is made in substantially 55 a zig-zag form for the purpose of reflecting the light rays from lamp 3 toward sign board 1 with a uniform intensity, and it is adapted to distribute the light 60 equally over all portions of the sign as well as to reflect the light rays into the depressions that may appear on the sign. Baffle plates 17 are pivoted respectively, to plates 18 fixed to transverse support 7 and to plate 19 fixed to transverse support 8. Pivot 20 65 fixed to each end of baffle plate 17 extends

into spaced apart holes 19' in plates 18 and 19 respectively. The baffle plates are uniformly spaced apart and in a parallel relation to one another and are held against individual movement by cross bar 21 pivotally connected to the bottom edges of the baffle plates at 22 and extending horizontally from one baffle plate to the other. Cross bar 21 is provided with longitudinal slot 21' to receive bolt 23 mounted in the 70 column and said cross bar is secured in any adjusted position desired by wing nut 24. Lamp 3 has conductors 25 connected thereto and extending through hole 26 in reflector 4, through a perforation into vertical tube 5 and through the vertical tube to suitable outside electrical current supply, or to storage batteries in the base of the columns. 75

The operation and mechanical operative features of my invention are substantially as follows:

Reflector 4 containing lamp 3 is positioned adjacent the lower end of vertical tube 5 and reflector 4' containing lamp 3' is positioned adjacent the upper end of vertical tube 5'. Assuming that zig-zag reflectors 16 and 16' are adjusted with relation to reflectors 4 and 4' so that light rays from the lamps 3 and 3' are reflected inwardly toward the front of sign board 1 at a desired angle, reflectors 4 and 4' are adjusted for directing light rays, respectively, from lamps 3 and 3' across the front of sign board 1 and are fixed to vertical tubes 5 and 5', respectively, by tightening nuts 27, as clearly shown in Fig. 4 for securing clamping brackets 6 to the vertical tubes. Thumb screws 14 may then be loosened for final adjustment of reflectors 4 and 4' for directing the rays of light from lamps 3 and 3' respectively toward the surface of the usual sign fixed to the front of sign board 1. Cross bar 21 is adjusted to properly position the edges of baffle plates 17 to deflect the rays of light inwardly toward the sign and are fixed in position by tightening wing nut 24. The light rays are thereby reflected from lamps 3 and 3', respectively, by reflectors 4 and 4' across their respective one-half front surface of the sign, respectively, in contact with an oppositely disposed zig-zag reflector 16' and 16 whereby the light rays are reflected toward and across the front surface of the sign as well as in other directions caused by the zig-zag form of the reflector whereby the sign is illuminated with uniform intensity. It is therefore apparent that I am enabled by the use of my invention to utilize a ray of light more than one time. The increased lighting effects on the sign secured thereby are dependent upon the efficient adjustment of reflectors 4 and 4', baffle plates 17 and zig-zag reflectors 16 and 16'. As shown in 130

Fig. 2 baffle plates 17 deflect the rays of light from lamp 3 which ordinarily would be reflected by reflectors 4 and 4' outside the plane of the front of the sign. The 5 baffle plates thereby increase the volume of light on the sign and prevent the lamp being seen by passers by no matter at what angle from which the sign may be viewed. The zig-zag reflectors 16 and 16' are preferably placed at a slight angle relative to the sign board as by placing the outside edge 10 16'' slightly toward the center of the sign thus causing the rays of light to be reflected inwardly toward the sign, thereby efficiently 15 and effectively illuminating depressions, elevations and the like on all portions of the sign. The reflectors 4 and 4' are preferably positioned so as to reflect the rays of light from lamps 3 and 3', respectively, diagonally across the front of the sign, the rays 20 of light from lamp 3 covering that portion of the sign not covered by the rays of light from lamp 3'. The light rays when reflected by zig-zag reflectors 16 and 16' 25 toward the center of the sign are distributed over its entire surface thus effecting a uniform illumination without considerable loss of the volume of light rays being absorbed by objects other than the sign. Therefore, 30 by the use of my invention, I obtain equal illumination of a sign board by the use of considerably less candle power than is required to illuminate sign boards by the usual illuminating means and methods of 35 reflecting the light rays as has been customary in the past.

I have chosen to illustrate one form of construction of my invention by means of which a sign board may be efficiently illuminated with a considerable saving in the candle power required, but the showing made by me has been more for illustration and without attempt of completeness and I desire to emphasize the fact that various forms not 40 shown by me may be adapted for use of my invention, such as, for instance, where, as shown in Fig. 1 my structure discloses only one lamp in each column and in a preferred position, as many lamps as desired and in 45 various positions, may be used. It is, therefore, to be understood that it is not intended to confine the invention to the forms of embodiments herein disclosed because it is susceptible of embodiments of various forms 50 all coming within the scope of the claims.

What I claim as new and desire to secure by Letters Patent is:

1. In a sign, a lamp partly concealed near the top and slightly in front of the face of 55 the sign, a reflector fixed to said lamp and adapted to direct the light rays across substantially one-half of the surface of the sign, and a reflector upon the opposite vertical edge of the sign to direct the rays of light 60 diagonally across the other half of the sign.

2. A sign having a front display surface upon which the display matter is mounted, hollow posts at each side or end of said sign adapted to support the sign, said posts having a vertical opening adjacent the sign, a 70 light displayed within one of said hollow posts near the top thereof and in the other post near the bottom thereof and a vertical reflector along each vertical edge of the sign whereby the rays of light are redirected 75 across the surface of said sign to thoroughly and evenly distribute said light rays over the entire surface of the sign.

3. In a sign, a lamp concealed near the top and slightly in front of the face of said sign, 80 a reflector fixed to said lamp and adapted to direct the light rays across substantially one-half of the surface of the sign and a zig-zag reflector upon the opposite vertical edge of the sign adapted to re-reflect the light rays 85 over the entire surface of said sign with uniform intensity, substantially as and for the purposes specified.

4. In a stationary sign having hollow posts at each side adapted to support said sign, a lamp mounted in each of said posts and a reflector adjacent each of said lamps adapted to reflect the light rays from said lamp across the surface of said sign, a zig-zag reflector slightly inclined inwardly 90 extending vertically with the edge of said sign and adapted to re-reflect the light rays over the entire surface of said sign with uniform 95 intensity, baffle plates pivotally connected in said hollow posts and adapted to be adjusted whereby the light rays from said lamp are adapted to be deflected toward the front surface of said sign and away from the range of vision of passers-by, substantially 100 as and for the purposes specified.

5. In a stationary sign having hollow posts at each side adapted to support said sign, a lamp mounted in each of said posts and a reflector adjacent each of said lamps adapted to reflect the light rays from said lamp across the surface of said sign, a zig-zag reflector slightly inclined inwardly 110 extending vertically with the edge of said sign and adapted to re-reflect the light rays over the entire surface of said sign with uniform intensity, a baffle plate adjacent the lamp whereby the light rays from said lamp are adapted to be deflected toward the front surface of said sign and away from the range of vision of passers-by, substantially 115 as and for the purposes specified.

6. In a sign, a stationary post, a tube pivotally mounted therein, a lamp mounted on said tube, a disk supporting said tube and having an indicating finger thereon and a gauge whereby said indicating finger may be accurately adjusted to properly focus the lamp and reflector with relation to the sign.
